UNITED STATES PATENT OFFICE.

ERNEST J. BRASSEUR, OF CHICAGO, ILLINOIS, ASSIGNOR, BY MESNE ASSIGNMENTS,
TO A. B. DICK COMPANY, OF CHICAGO, ILLINOIS, A CORPORATION OF ILLINOIS.

STENCIL DUPLICATING MACHINE.

Application filed October 3, 1922. Serial No. 592,045.

To all whom it may concern:

Be it known that I, ERNEST J. BRASSEUR, a citizen of the United States, residing in the city of Chicago, county of Cook, and 5 State of Illinois, have invented certain new and useful Improvements in Stencil Duplicating Machines, of which the following is a specification.

The invention relates to stencil-duplicating machines, and has reference more particularly to inking mechanism for use with such machines.

The aim of my invention is to provide for duplicating machines an improved inking mechanism which may be operated readily, easily and quickly to supply and distribute a controllable quantity of ink over any desired portion of the machine's printing cylinder. Another object of my invention is to provide an inking device having an ink reservoir which may readily and easily be associated with or be removed from a duplicating machine, and so arranged as to decrease any tendency of the ink to spill therefrom, either while mounted in the duplicating machine or when removed therefrom, and to be at all times readily accessible and conveniently positioned for filling. Another object of my invention is to 25 provide an inking device which is light, convenient and fast to operate. Another object of my invention is to provide a duplicating machine with an easily removable printing cylinder and with means operable 30 to distribute ink to said cylinder and also adapted to function as means for cleaning the cylinder when the cylinder is removed. A further object of my invention is to 35 provide an inking device incorporating automatically operating means for preventing discharge of ink at inopportune times. Other objects of my invention will be in 40 part obvious and in part pointed out hereinafter.

45 In inking devices now in use the ink tank, the brush and the brush rod are attached together for simultaneous rotation, and in consequence, when the brush is oscillated, the tilting of the tank, and also 50 centrifugal force set up by the oscillation, tend to force ink out of the tank valves and the filling opening. After only short usage the tank will be quite covered with ink dripped from the accumulation on the

brush. The ink tanks are usually quite 55 heavy, especially when filled, and their movement with the oscillating brush very often pounds the operating parts of the machine out of alignment. In these constructions the ink tank is permanently 60 mounted on the duplicating machine, and the filling opening of the tank is usually in an inaccessible position near the center of the printing cylinder, thus making filling difficult.

In accordance with my invention, the ink tank is not mounted for rotation or oscillation with the brush or brush rod, but is 65 independent of their movements, being 70 slidably mounted and held in vertical position on a separate cradle therefor, which is designed to be removably mounted on the machine. By this means I not only avoid the above mentioned objectionable features 75 present in prior constructions, but also produce a device which is faster, easier, and more convenient to operate, since to distribute ink to the cylinder it is not necessary to oscillate the tank but only the brush and its operating parts, which are light. 80 The ink tank is equipped with the usual discharge valve which is manually operative from a rotatable knob at the top of the tank; and to prevent discharge of ink from this valve at undesired times I provide 85 means for automatically locking the valve against opening except when the tank is in proper position with respect to the ink distributing brush and the cylinder. I provide a brush operating handle which is held 90 stationary when the cylinder rotates but by means of which the brush may be moved to any desired portion of the cylinder and be oscillated to distribute thereto ink fed from the ink tank. When mounted in a machine 95 the ink tank presents a filling opening well above the printing cylinder so as to be readily accessible for filling. The ink tank is so arranged that it may readily and easily 100 be moved on its cradle into and out of operative position with respect to the printing cylinder, and means are provided for automatically locking the tank in inoperative position. The cradle ends are so designed that when the cradle is out of the 105 machine, the cradle firmly supports itself and the ink tank in upright position, thus preventing leakage. The printing cylinder

is mounted for removal with the brush and its operating means from the machine, and when so removed, the brush may be employed to clean the cylinder.

5 In order that a clearer understanding of my invention may be had, attention is hereby directed to the accompanying drawings forming a part of this application and illustrating one possible embodiment of my

10 invention. Referring to the drawings, Fig. 1 is a side elevation of a portion of a stencil duplicating machine embodying my invention; Fig. 2 is a perspective view of the ink tank and cradle of the inking mechanism; Fig. 3 is a transverse sectional view taken on the line 3—3 of Fig. 1; Fig. 4 is a plan view of the brush operating mechanism of the inking device; Fig. 5 is a longitudinal sectional view of the mechanism shown in Fig. 4; Fig. 6 is a sectional view taken on the line 6—6 of Fig. 3; and Fig. 7 is a side plan view of the printing cylinder showing the means, partly in section, for removably holding the cylinder on the machine. Similar reference characters refer to similar parts throughout the several views of the drawings.

Referring to the drawings, the stencil duplicating machine proper comprises the usual spaced side members 1 and 2, rotatable printing cylinder 3, impression roller 4, driving gears 5, and crank handle 6 for rotating the printing cylinder. The inking mechanism includes a cradle 7 and an ink tank 8, which is slidably mounted on parallel rods 9 extending between end spiders 10 and 11 of the cradle. End member 10 has a vertical central offset portion 12, near the top of which extend opposite lateral arms 13, and near the bottom of which extend opposite lateral legs 14. The opposite end member 11 has a T-shaped upper portion 15 and an offset, forked lower portion 16. The rods 9 extend between and are secured to arms 13 of member 10 and the top portion 15 of member 11. The ends of the rods 9 protrude on the outside of member 10, as at 17, and protrude from the outside of member 11, as at 18. The support 1 of the duplicating machine has small vertical slots or notches for the protruding ends 18 of the rods 9, and the duplicating machine support 2 has similar small slots or notches 19 for the protruding ends 17 of the rods 9. Support 2 has also a vertical radial slot 20 to permit the removal of the printing cylinder, as will be described hereinafter. Offset 12 of cradle member 10, however, is arranged to removably seat in this slot 20 and to act as a filler therefor. With this arrangement the ink tank may readily and easily be mounted in place in the duplicating machine by merely placing the cradle in position with the rod ends and the offset portion 12 in the respec-

tive slots provided therefor in the supporting members 1 and 2 of the duplicating machine. The ink tank and its cradle may be removed from the duplicating machine by merely lifting it out of the same, and when it is so removed, the ink tank cradle 7 supports itself, and the ink tank mounted thereon, upright on spread legs 14 and 16. The ink tank 8 has a filling opening at the top; and a removable sealing cap 21 is provided therefor. Tank 8 is high with respect to the printing cylinder so as to be readily accessible and in a most convenient position for filling the tank. At the bottom of tank 8 is a discharge valve 22 which is manually operable by means of a rotatable knob 23 mounted on the top of the tank.

The ink distributing brush 24 is suspended from one end of a brush tube 25 by means of an arm 26, the length of which is adjustable, as at 27. Cylinder 3 has a hub 28 rigidly attached thereto, which carries a sleeve 29, penetrating the hub 28 and secured thereto, as by set screws 30, for rotation therewith. Sleeve 29 extends outwardly of printing cylinder 3 and seats in a bearing 31, and also extends inwardly of hub 28 to form a bearing for the brush tube 25 which is slidably enclosed by sleeve 29, but is frictionally engaged thereby so that the brush and brush tube will rotate with the cylinder. The axially perforated cylinder 3, is rotatable about the usual stub-shaft 32 which is carried on support 1 at the opposite side of the machine. The rotation of the cylinder is effected in the usual manner by means of an arm 33 which has a pin 34 removably seated in a perforation on the side of the printing cylinder 3. Arm 33 is rotatable from crank handle 6.

The brush tube 25 encloses a rod 35, the outer end of which is secured, as at 36, to the inner end of a handle 37 which is positioned on the outside of side member 2. Rod 35 is slidable relatively to the tube 25, so that by grasping handle 37 and moving it outwardly rod 35 may be slid outwardly of tube 25. Pivoted on rod 35, as at 38, is a latch 39 which has a head 40 arranged to lock within an annular recess 41 provided in tube 25, so that thereafter inward or outward movement of handle 37 causes similar movement of brush tube 25 and brush 24. Spring 42 carried by the handle presses the latch toward locking position, and the latch 39 may be unlocked from this recess by pushing upon pin 43, which is slidably mounted in handle 37 and has its inner end engaging latch 39. Tube 25 contains near its center an annular member 44, which is notched, as at 45, to receive a pin 46, provided near the end of rod 35, when latch 39 engages recess 41. When this engagement has been made, oscillation of handle 37 will cause similar oscillation of tube 25 and of the

brush 24 carried thereby. A retainer 47 for the handle is preferably attached, as by means of screws 48, to the outside of supporting member 2. This retainer 47 provides two resilient prongs 49 which are adapted to receive a ferrule 50 at the base of handle 37 and resiliently hold handle 37 in horizontal position.

The valve operating knob 23 of the ink tank carries gear teeth 51 which are in permanent mesh with a gear segment 52 carried at the top of a lever 53 which is pivoted to the side of the ink tank 8 by means of screw 54. The lower end 55 of lever 53 is arranged to engage against the side of brush tube 25 and thereby prevent the turning of the knob 23 to open the feed valve 22 of the tank. In order to permit of the operation of the knob 23 to open the feed valve 22, the ink tank 8 and locking lever 53 must be beyond the end of the brush rod 25, and consequently also beyond the brush 24. Thus it is seen that by the above means the feeding of ink from the tank is prevented when it would fall upon the brush rod or on other parts where it is not desired, but that the ink can be easily fed to the interior of the printing cylinder. Before the printing cylinder is rotated, ink tank 8 is moved to inoperative position outside of the printing cylinder into a space provided between the side of the cylinder and side member 2, as shown by dot and dash lines in Fig. 3. When tank 8 has been moved into this position, a headed pin 56 provided on locking lever 53 is adapted to enter a recess 57 provided for this pin in the side member 2 of the machine. When pin 56 is in recess 57, knob 23 is prevented from turning and the feed valve 22 of the tank is locked in closed position.

I also provide means for locking the ink tank 8 in this inoperative position, so that it may not accidentally move into contact with the rotating printing cylinder. To this end I provide an angular lever 58 pivoted at one end, as at 59, to the inside of side member 2 of the machine below bearing 31. I provide a coil spring 60 about pivot 59, which at one end engages a pin 61 on lever 58 and at the other end engages a pin 62 on side member 2, the spring urging lever 58 upwardly. The lower surface of bearing 31 serves as a stop for lever 58. Extending from lever 58 is a projecting arm 63, which is positioned to be engaged and moved downwardly by ferrule 50 of handle 37 as this handle is moved from vertical position, shown in dot and dash lines in Fig. 3, to horizontal position and into engagement with its retainer 47, this movement causing downward movement of the lever 58. The arrangement is such that when handle 37 is in horizontal position in its retainer 47, the upper end 64 of lever 58 engages behind

the head of the pin 56 of the ink tank locking lever 53, and the ink tank is locked against side member 2 and in inoperative position. When handle 37 is raised out of its retainer 47, spring 60 moves lever 58 upwardly, causing its upper end 64 to move from behind the head of pin 56, thereby unlocking the ink tank from side member 2 and permitting it to be moved over the cylinder. Should the handle 37 be placed in horizontal position within its retainer 47 before ink tank 8 is moved to its inoperative position, then, when the tank is moved into this position, the head of pin 56 will strike the top 64 of lever 58 so as to cam it aside against the action of spring 60, and when the head of pin 56 has become seated in recess 57, spring 60 will automatically move the top 64 of lever 58 behind the head of the pin, thus automatically locking the tank in inoperative position.

The bearing 28 for the cylinder supporting sleeve 30 comprises a lower portion 65 rigidly secured to the side member 2 and an upper half 66, which is extended inwardly of portion 65, as at 67, and is pivoted to the lower portion 65, as at 68. A bolt 69 pivoted to member 65, as at 70, is adapted to seat within a notch 71 provided therefor in member 66, and a wing nut 72 is provided for bolt 69 to hold the two halves 65 and 66 of the bearing together. To remove the printing cylinder, the cradle with its ink tank is lifted out of the machine, and then wing nut 72 is loosened and disengaged from bearing member 66, and this member is swung upwardly. The cylinder may then be moved laterally toward bearing portion 65 to bring it out of engagement with stub shaft 32 and pin 34 and then the cylinder 100 may be lifted upwardly out of the machine. The slot 20 provides a clear upward passage for the sleeve 29. The cylinder may as easily be remounted in the machine.

When the cylinder has been so removed, the brush and handle remain intact in the cylinder and may be used to clean the diaphragm of the cylinder by oscillating the brush while submerged or held under running water.

From the above, the operation of the machine will be readily apparent. When it is desired to feed and to distribute ink to a portion of the cylinder, the handle 37 is raised out of its retainer 47. This operation unlocks the ink tank 8 from side member 2 for movement along its cradle. Ink tank 8 is then moved to the proper place over the cylinder beyond brush rod 25, and by manipulating knob 23 the desired quantity of ink is fed to the interior surface of the printing cylinder. Handle 37 is then pulled outwardly until the engagements are effected between latch 39 and recess 41, and also between pin 46 and notch 45, whereby brush 24

is connected with handle 37 for operation thereby. Then the handle 37 is moved inwardly or outwardly and oscillated to effect the desired movements of brush 24 over and 5 in contact with the interior surface of cylinder 3 to distribute the ink fed from tank 8 over the desired portions of the cylinder. When the distribution of ink has been effected, pin 43 of handle 37 is pushed inwardly and handle 37 moved toward side support 2 and locked in its retainer 47. Ink tank 8 may have been previously moved into inoperative position against side member 2 and outside of the cylinder, or it may 10 now be moved into such position, and in either case will be automatically locked in such position by means of the coaction between pin 56 and lever 58. Upon subsequent rotation of the printing cylinder, the 15 brush tube 25 and brush 24 will rotate therewith while handle 37 remains stationary. As many changes could be made in the 20 above construction and many apparently widely different embodiments of this invention could be made without departing from the scope thereof, it is intended that all matter contained in the above description or shown in the accompanying drawings shall be interpreted as illustrative and not in 25 a limiting sense.

What I claim is:—

1. A stencil duplicating machine having a cradle removably mounted therein and an ink tank slidably mounted on said cradle, 30 said ink tank adapted to be moved out of the line of the printing action.
2. A stencil duplicating machine having a cradle removably mounted therein and an ink tank slidably mounted on said cradle, 35 said cradle being arranged to maintain it self and said ink tank in upright position when removed from said machine.
3. In a stencil duplicating machine, in 40 combination, side members, a cradle removably mounted between said side members and supported thereby, said cradle having projections removably seated in notches provided by said side members, and an ink tank slidably mounted on said cradle.
4. In stencil duplicating machines, the 45 combination with side supports and a printing cylinder between said supports, of a cradle removably supported between said side supports and having projections extending from both sides and an offset portion on one side, notches on said side supports for removably receiving said projections and a slot on one side support for removably receiving said offset portion, and 50 an ink tank supported in vertical position by said cradle for slidable movement across said cylinder.
5. A stencil duplicating machine having a 55 cradle removably mounted therein and an ink tank slidably mounted on said cradle, and means for locking said ink tank in pre-determined position on said cradle; said ink tank adapted to be moved in said cradle outside of the line of the printing action.
6. In a stencil duplicating machine, in 60 combination, side members, an ink tank, means supporting said ink tank for sliding movement between said side members, a rotatable printing cylinder between said side members positioned to provide space for said ink tank between one of said side members and a side of said cylinder, and means for locking said ink tank in said space.
7. In a stencil duplicating machine, in 65 combination, side members, an ink tank, means supporting said ink tank for sliding movement between said side members, a rotatable printing cylinder between said side members positioned to provide space for said ink tank between one of said side members and a side of said cylinder, and means for locking said ink tank in said space; 70 said means comprising a headed pin movable with said tank and a lever mounted on the adjacent side member adapted to lock behind the head of said pin.
8. In a stencil duplicating machine, in 75 combination, side members, an ink tank, means supporting said ink tank for sliding movement between said side members, a rotatable printing cylinder between said side members positioned to provide space for said ink tank between one of said side members and a side of said cylinder, and means for locking said ink tank in said space; 80 said means comprising a headed pin movable with said tank and a lever mounted on the adjacent side member adapted to lock behind the head of said pin.
9. In a stencil duplicating machine, in 85 combination with a rotatable printing cylinder, of an ink distributing brush mounted within said cylinder and connected thereto for rotation therewith, and manually operative means for moving said brush axially and rotatively with respect to said cylinder.
10. In a stencil duplicating machine, the 90 combination with a side support and a printing cylinder rotatably mounted thereon, of a brush tube slidably extending axially into said cylinder, an ink distributing brush supported from the end of said brush tube within said cylinder, a rod slidably positioned within said tube, a handle engaging one end of said rod outside of said side member, and means comprising a latch on said rod adapted to lock within a recess in said tube to lock said rod and tube together for simultaneous movement across said cylinder.
11. In a stencil duplicating machine, the 95

- combination with a side support and a printing cylinder rotatably mounted thereon, of a brush tube slidably extending axially into said cylinder, an ink distributing brush supported from the end of said brush tube within said cylinder, a rod slidably positioned within said tube, a handle engaging one end of said rod outside of said side member, and means, comprising a pin on said rod adapted to engage within a notch in said tube, whereby oscillation of said handle causes oscillation of said brush within said cylinder.
12. In a stencil duplicating machine, the combination with a side support and a printing cylinder rotatably mounted thereon, of a brush tube slidably extending axially into said cylinder, an ink distributing brush supported from the end of said brush tube within said cylinder, a rod slidably positioned within said tube, a handle engaging one end of said rod outside of said side member, means comprising a latch on said rod adapted to lock within a recess in said tube to lock said rod and tube together for simultaneous movement across said cylinder, and means, comprising a manually movable pin carried by said handle and engaging said latch for unlocking said latch from said recess, to permit movement of said rod inwardly of said tube.
13. In a stencil duplicating machine, in combination, a side member, a rotatable printing cylinder, means for rotating said cylinder, an ink distributing brush within said cylinder, a handle, and means adjustable to connect said brush to said handle for operation thereby and adjustable to disconnect said brush from said handle to permit rotation of said brush with said cylinder independently of said handle.
14. In a stencil duplicating machine, in combination, a side member, a rotatable printing cylinder, means for rotating said cylinder, an ink distributing brush within said cylinder, a handle, and means adjustable to connect said brush to said handle for operation thereby and adjustable to disconnect said brush from said handle to permit rotation of said brush with said cylinder independently of said handle, said means comprising a brush tube connected with said brush and a rod slidably within said tube and connected with said handle and a severable connection between said tube and rod effective when said rod and tube are in one relative position and ineffective when said rod and tube are in another relative position.
15. In a stencil duplicating machine, in combination, a side member, a rotatable printing cylinder, means for rotating said cylinder, an ink distributing brush within said cylinder, a handle, and means adjustable to connect said brush to said handle for operation thereby and adjustable to disconnect said brush from said handle to permit rotation of said brush with said cylinder independently of said handle, said means comprising a retainer on said side member, 70 for holding said handle stationary while said cylinder and brush rotate.
16. In a stencil duplicating machine, in combination, a printing cylinder, ink distributing means, including a brush movable over and in contact with the interior surface of said cylinder, and ink feeding means, including an ink tank movable independently of said brush across said cylinder, and means coacting with both of said means 80 when said brush and tank are in predetermined relative positions for preventing feeding of ink by said feeding means while said brush and tank are in such relative positions.
17. In a stencil duplicating machine, in combination, a printing cylinder, ink distributing means, including a brush tube mounted for sliding movement inwardly and outwardly of said cylinder and a brush supported on said tube, ink feeding means, including an ink tank movable independently of said brush and tube across said cylinder and provided with operable feed valve mechanism, and means engaging said 95 feed valve mechanism and adapted to coact with said brush tube when said brush and tank are in predetermined relative positions for preventing valve opening operation of said feed valve mechanism while said brush and tank are in such relative positions.
18. In a stencil duplicating machine, in combination, a printing cylinder, ink distributing means, including a brush tube mounted for sliding movement inwardly 100 and outwardly of said cylinder and a brush supported on said tube, ink feeding means, including an ink tank movable across said cylinder and provided with operable feed valve mechanism, including a rotatable 105 knob provided with gear teeth, a lever pivoted on said ink tank and having teeth engaging with the teeth of said knob, the opposite end of said lever being arranged to engage against the side of said brush tube when said brush and tank are in predetermined relative positions to prevent the operation of said feed valve mechanism to feed ink while said brush and tank are in such relative positions.
19. In a stencil duplicating machine, in combination, side members, a removable cradle mounted in said side members, ink feeding means arranged on said cradle, a printing cylinder between said side members and bearings for said printing cylinder mounted on said side members, one of said side members having a slot extending to the 115 said bearing thereon, and said bearing hav-

ing a pivoted upper portion movable to permit said cylinder to be removed from said side members.

20. In a stencil duplicating machine, in combination, a printing cylinder having on one side an axial perforation and having on the other side an outwardly extending axial sleeve, a side member having a stub shaft seated within said perforation, and another side member having a bearing for said sleeve, said bearing comprising a fixed lower portion and a movable upper portion extending inwardly of said lower portion, whereby when said upper portion is in one position said cylinder is maintained in engagement with said stub shaft and when said upper portion is in another position

said cylinder may be moved sidewise to disengage from said stub shaft.

21. In a stencil duplicating machine, in combination, a printing cylinder, an ink distributing brush and brush operating mechanism mounted on said cylinder, said brush operating mechanism permitting said distributing brush to be rotated independently thereof, and means adjustable to maintain said cylinder on the machine, and adjustable to permit removal of said cylinder with said brush and operating mechanism intact therewith from the machine.

This specification signed this 25th day of September, 1922.

ERNEST J. BRASSEUR.
